US0D1044277S

(12) United States Design Patent (10) Patent No.: US D1,044,277 S
(45) Date of Patent: * Oct. 1, 2024

(54) STORAGE BOX

(71) Applicant: NINGBO BOTONG PLASTIC CO., LTD, Ningbo (CN)

(72) Inventor: Junhao Tong, Ningbo (CN)

(73) Assignee: NINGBO BOTONG PLASTIC CO., LTD, Ningbo (CN)

() Term: 15 Years

(21) Appl. No.: 29/847,527

(22) Filed: Jul. 26, 2022

(30) Foreign Application Priority Data

Jun. 7, 2022 (CN) 202230344893.7

(51) LOC (14) Cl. 09-04

(52) U.S. Cl.

USPC D3/304; D3/307

(58) Field of Classification Search
